UNITED STATES PATENT OFFICE.

EUGENE H. BALLOU, OF PAWTUCKET, RHODE ISLAND, ASSIGNOR TO DRAPER CORPORATION, OF HOPEDALE, MASSACHUSETTS, A CORPORATION OF MAINE.

FEELER MECHANISM FOR LOOMS.

Application filed December 13, 1924. Serial No. 755,799.

To all whom it may concern:

Be it known that I, EUGENE H. BALLOU, a citizen of the United States, and resident of Pawtucket, county of Providence, State of Rhode Island, have invented an Improvement in Feeler Mechanism for Looms, of which the following description, in connection with the accompanying drawings, is a specification, like characters on the drawings representing like parts.

This invention relates to feeler mechanisms for looms, and more particularly to that type of feeler mechanisms wherein the feeler is given a movement in a direction longitudinally of the shuttle when the filling is substantially exhausted on a detecting beat.

The feeler of such mechanisms is usually provided with a toothed filling engaging end to restrain movement of the feeler lengthwise of the shuttle when a working supply of filling is present on a detecting beat. The constant impact of the toothed end of the feeler against the filling is liable to injure the filling, especially when it is of fine count yarn, or of delicate character. This injurious impact is emphasized by the fact that the teeth sustain the full impact of the filling and by such impact move the feeler frontwardly in opposition to the usual means, such as a feeler spring for normally projecting the feeler into its rearward feeling position.

One of the objects of the present invention is to provide a feeler of the type referred to wherein the toothed or tip end portion of the feeler is yieldingly mounted to receive the first impact of the filling on a detecting beat and then yield frontwardly relative to the feeler to permit the smooth end portion of the feeler itself to take the full and complete impact of the filling whereby the feeler is moved frontwardly against the usual feeler spring.

When the filling is substantially exhausted on a detecting beat and the feeler moves longitudinally along the filling carrier, it is desirable that the toothed end portion of the tip of the feeler will not retard or obstruct movement of the feeler at the critical time, and to this end the present invention contemplates forming the toothed end of the feeler tip with a trailing tooth having a rounded surface which may move along the filling carrier or bobbin without injury

thereto and without obstructing the movement of the feeler.

It has been found in practice with a feeler tip formed as hereinbefore noted and, as will hereinafter be described, that a very delicate action of the feeler tip yielding means or spring is required, the energy of the spring being only sufficient to cause the teeth of the feeler to engage the filling and hold the feeler from premature side swipe movement. Such a spring is preferably formed of leaf character and another important feature of the invention therefore consists in providing a spring for normally projecting the toothed end of the feeler tip beyond the rear end of the feeler but sensitively yielding in a forward direction on the impact of the filling to permit the end of the feeler itself to receive the full impact on a detecting beat.

The above features of the invention and additional novel combination of parts will best be made clear from the following description and accompanying drawings of one good form of the present invention.

In the drawings:—

Fig. 1 is a perspective view of the feeler end of a loom provided with the present invention, some of the loom parts being omitted.

Fig. 2 is an enlarged perspective view, showing the end portion of the feeler and feeler tip.

Fig. 3 is an enlarged section plan view, showing the relation of parts when, on a detecting beat, a working supply of filling is in the shuttle.

Fig. 4 is a similar view, showing the first position of parts when the feeler detects substantial exhaustion of filling in the shuttle and before the feeler partakes of its side swipe movement.

Fig. 5 is a view similar to that of Fig. 4, showing the feeler as moving longitudinally along the filling carrier or bobbin; and

Fig. 6 is a sectional plan view of a modified form of the invention.

The general purpose of a feeler mechanism being to effect a change in the loom operation when the filling is substantially exhausted in the shuttle, and more particularly to effect replenishment of the filling under the described conditions, and the train of mechanism for bringing about such

change in the loom operation being now well understood, it has not been deemed necessary herein to illustrate and describe the replenishment mechanism in detail.

5 The loom parts such as the frame and other details may be substantially as usual, and, as shown in the present instance of the invention, the transverse or rock shaft usual in this type of loom (not shown), has rising therefrom the arm 1, to which is pivoted at 2 the actuator 3, the rear end portion of which is provided with a finger 4 pivoted to the actuator at 5, the rear end portion 6 of the finger being adapted at times for 10 engagement with an operating member 7, which may be formed as part of or actuated from the cam follower.

Extending upwardly from the shipper stand 8 is a lug 9 to which is secured at 10 20 a support 11 having pivotally mounted thereon at 12 a bell crank lever the horizontal arm 13 of which underlies a projection 14 secured to the finger 4. The downwardly extending arm 15 of the bell crank 25 lever is connected to a transmitter 16 which is secured at 17 to a slide 18 mounted in suitable guideways 19 at the rear of the feeler stand 20. The slide 18 has an opening 21 thru which the feeler 22 extends, and at the 30 front portion of the feeler stand 20 is a swivel block 23 thru which the stem 24 of the feeler extends.

The shipper stand 8 has a projecting portion 25 to which is secured a bracket 26 35 which serves to support the feeler stand in adjusted position by means of a bolt 27, and a spring 28 interposed between the bridge 29 secured to the feeler and swivel block 23 normally serves to project the feeler into 40 its rearward feeling position. The parts so far described are or may be substantially the same as the similar parts in the patent to Edward S. Stimpson, No. 1,309,226, and need no further description.

45 The lay 29, is of usual character, and has the shuttle box 30, the front wall of which has an opening 31, as has also the shuttle 32, as described in the Stimpson patent, so that on a detecting beat the end 50 of the feeler may feel thru the openings when a shuttle is in the detecting box and detect the condition of the filling.

In accordance with the present invention, the feeler 22 is provided with a yieldingly 55 mounted feeler tip having a plurality of teeth for taking the first impact of the filling on detecting beat and to be moved forwardly to enable the rear end portion of the feeler itself to take the full impact of the oncoming filling. As shown, the rear 60 end portion of the feeler at 33 is provided with a housing for the reception of the feeler tip which is constituted as a block 34 having a series of teeth 35.

In the present instance the housing is formed by providing an opening 36 in the end portion of the feeler for the reception of the toothed block 34 and the opening thus formed is of suitable dimension to permit the toothed block to be moved normally with the teeth in a projected position beyond the end of the feeler, as indicated in Fig. 2, and to slide into the housing on the first impact of the filling to permit the rear end portion of the feeler itself to take the full frontward impact, the purpose of the teeth being merely to prevent premature side swipe movement of the feeler.

The housing at the end of the feeler is shown as having the side openings 37, one 80 being indicated at each side of the feeler, and secured to the feeler is a spring 38, one end 39 thereof being secured to the feeler forward of the slot 36 to afford support for the spring. The spring 38 is shown as of the sensitive leaf type and is provided with a coil 40 from which extends an end portion 41 of the spring which passes thru the slots 37 formed in the side of the feeler housing and is secured to the block 90 34. The slots 37 are elongated, as shown, and the rear walls 42 of the slots are engaged by the end portion 41 of the spring when the feeler tip 34 is in projected position, so that a part of the spring 38 acts as a stop to determine the projected position of the feeler tip. When the block 34 with the series of teeth thereupon is in projected position as indicated in Fig. 2, the end portion 41 of the spring rests against the shoulders 42 of the housing slots 37, and on impact of a surface within the shuttle against any tooth of the block, the sensitive character of the spring first causes the teeth to engage the filling with holding effect 105 without unduly sinking into the filling, and then the portion 41 of the leaf spring is moved frontwardly to permit the teeth of the block 34 to move within the housing, as indicated in Fig. 3.

In securing the sensitive leaf spring to the feeler and toothed block, the present construction shows the end 39 of the spring passed thru an opening in the feeler forward of the housing and the other end 41 115 of the spring passed thru an opening in the toothed block, the result being that the end portion 41 of the spring may engage the walls 42 of the slots 37 to thereby limit the rearward movement of the feeler tip.

When the filling is substantially exhausted on a detecting beat, it is desirable that the toothed portion of the block 34 shall present no obstruction to the sensitive movement of the feeler along the filling carrier, and to this end the trailing tooth 43 of the series of teeth on the block 34 is provided with a rounded surface 44, the effect being

that when the filling is substantially exhausted, as indicated in Fig. 4, the rounded surface 44 of the trailing tooth 43 will engage the surface of the bobbin or filling carrier, or the few turns of filling still left thereon, so that the feeler itself is then free to move along the filling carrier without obstruction by the teeth of the block, or injurious effect upon the filling carrier or bobbin itself, such movement being indicated initially in Fig. 4, and as taking place or nearly completed in Fig. 5. In Fig. 5 it will be noted that, while the tooth 43 is engaged with the surface of the filling carrier, the rounded portion 44 of the trailing tooth rides along the surface of the filling carrier or bobbin and holds all of the other teeth of the series out of engagement with the surface of the filling carrier or bobbin.

20 As a further means for facilitating the movement of the feeler longitudinally along the filling carrier or bobbin when the filling is substantially exhausted on the detecting beat, the rear end portion of the feeler itself 25 has the trailing surface 45 formed rounded, with the result that not only does the rounded surface of the trailing tooth 43 ride along the filling carrier or bobbin, but likewise does the rounded surface 45 of the end of 30 the carrier itself.

Inasmuch as the rear end portion of the feeler 22 takes the full impact of the filling on a detecting beat, it may be desirable at times, especially with fine filling, to provide 35 the end of the feeler with a cushion. This construction is shown in the modification of Fig. 6, wherein the end of the feeler is provided with a cushion material 46 which may extend over the rear end portion of the 40 feeler as shown and have its side portions 47 turn frontwardly into suitable recesses formed in the sides of the end portion of the feeler; the result being that when the feeler takes the full impact of the filling on 45 a detecting beat, the cushion material 46 will not injure the filling, and when the feeler side swipes, the rounded surface of the cushion material 46 at the trailing side thereof will slide along the filling carrier 50 without injurious effect.

What is claimed is:—

1. In a feeler mechanism for looms, the combination of a side swipe feeler mounted for yielding frontward movement and sliding movement longitudinally of a surface within the shuttle, a feeler tip slidably mounted upon the feeler for yielding frontward movement and having an integral row of teeth extending lengthwise of the shuttle 55 and which normally project from the rear end of the feeler to engage a surface of substantial area within the shuttle on a detecting beat and arranged so that as the feeler commences its side swipe movement the 60 teeth will be tilted out of engagement with the surface in the order of their arrangement.
2. In a feeler mechanism for looms, the combination of a side swipe feeler mounted for yielding frontward movement and sliding movement longitudinally of a surface 70 within the shuttle, a feeler tip slidably mounted upon the feeler for yielding frontward movement and having an integral row of teeth extending lengthwise of the shuttle, 75 the trailing tooth of the series having a rounded surface to slide along the filling carrier as the feeler partakes of its side-swipe movement and constructed to disengage the teeth from the surface within the 80 shuttle as the feeler partakes of its side-swipe movement, and a spring for urging the tip rearwardly so that the teeth normally project beyond the rear end of the 85 feeler.
3. In a feeler mechanism for looms, the combination of a side swipe feeler mounted for yielding frontward movement and sliding movement longitudinally of a surface 90 within the shuttle, a feeler tip comprising a block supported by the feeler for yielding frontward movement and having a wide end provided with a row of teeth extending lengthwise of the shuttle and which normally project from the rear end of the 95 feeler to receive the initial impact of the surface within the shuttle on a detecting beat and arranged so that pressure of said surface against one or more of the teeth will cause the tip as a whole to yield frontwardly to permit the end of the feeler to engage the surface within the shuttle. 100
4. In a feeler mechanism for looms, the combination of a side swipe feeler having a long narrow slot in its rear end and mounted for movement frontwardly under the frontward pressure of a surface within the shuttle upon its rear end and for movement longitudinally of the shuttle, a feeler tip 105 constituting a block that fits the long narrow slot and is yieldingly mounted therein for sliding movement and provided with a series of integral teeth arranged in a row lengthwise of the filling carrier and in position to normally project beyond the rear 110 end of the feeler to receive the initial impact of the surface within the shuttle on a detecting beat and arranged so that pressure of said surface against one or more of the teeth will cause the tip as a whole to yield frontwardly to permit the end of the feeler to engage the surface within the shuttle. 115
5. A feeler having an elongated slot formed in its end and provided with a tip 120 slidably in the slot and comprising a block shaped in cross-section to conform to the elongated slot, a series of teeth upon the rear end of the block and extending in a row lengthwise of the shuttle, and a spring 125 outside of the feeler and having one end 130

thereof secured to the feeler and the other engaging the block.

6. A feeler having a cushioned rear end and a tip constituted as a block slidably supported by the feeler and provided at its end with a series of integral teeth disposed in a row lengthwise of the filling carrier, a spring normally acting upon the block to project its teeth rearward from the end of
10. the feeler and constructed to yield under a frontward pressure upon the teeth to permit

the cushioned end of the feeler to engage a surface within the shuttle.

7. A feeler having a slotted end portion and provided with a tip, a spring outside of 15 and secured to the feeler and having one end thereof extending into the slotted end of the feeler and engaging the tip.

In testimony whereof, I have signed my name to this specification.

EUGENE H. BALLOU.
